SLIVER COILER

Olan Richardson, Hampton, and Charles W. Walter,
Griffin, Ga., assignors to Southern States Equipment
Corporation, a corporation of Georgia

Application June 25, 1958, Serial No. 744,510

13 Claims. (Cl. 19—159)

This invention relates to sliver coilers and more particularly to coilers using large cans provided with rollers or the like to facilitate bodily movement of the cans and their contents from one position to another.

It is customary to move sliver cans from place to place as a routine procedure in textile mills. Frequently the cans are moved manually by an operator who simply slides the cans along the floor in groups of five or six cans. The trend toward cans of larger and larger diameters results in substantial increases in the weight of the cans, particularly when filled with sliver. Thus with heavier cans to handle, it is becoming more and more difficult for an operator to move the cans about, especially where a particular operation requires him to slide a group of several cans along the floor. In some instances it is necessary for the operator to reduce the number of cans moved simultaneously in a group and by so doing partially to defeat the purpose of using larger cans.

A principal object of this invention is to provide an improved coiler having a can mounted on rollers and having a platform arranged to receive and to position the can properly as well as to hold the can securely in place while a coiling operation is effected.

Another object of this invention is the provision of an improved platform for sliver coilers wherein improved roller holding means are arranged to engage the can rollers and wherein improved guide means are utilized to engage the can rollers so as to guide the can into its proper position on the coiler platform.

The invention in one form comprises a coiler having a can with a plurality of rollers thereon and a platform having a plurality of roller holding means together with a plurality of roller guide means arranged to engage the can rollers and to guide them in to cooperative engagement with the roller holding means on the platform.

The invention will be better understood from the following detailed description taken in conjunction with the accompanying drawings in which Fig. 1 is a side view of a coiler having a wheel mounted can; in which Fig. 2 is a plan view of a coiler platform constructed according to this invention; in which Fig. 3 is an enlarged view taken along the line 3—3 of Fig. 2; and in which Fig. 4 is a plan view of a modification of the platform shown in Fig. 2.

With reference to Fig. 1 the numeral 1 designates a coiler base on which a pedestal 2 is securely affixed in conventional fashion. Mounted atop the pedestal 2 is a coiler head generally designated by the numeral 3. A can 4 is positioned on rotatable platform 5. As is well understood in the art suitable mechanism is disposed within the pedestal 2 for imparting rotary motion to platform 5 and in addition to impart suitable motion to a sliver fed into the top of the head 3 whereby the sliver is coiled in a predetermined pattern within the can 4.

As can be seen in Fig. 1 the can 4 is provided with a plurality of rollers 6.

According to this invention the rotatable platform 5 is constructed so as to hold the roller mounted can 4 in

2

position on the platform and so as to enable an operator readily to position the can 4 in its proper centered relation on the rotatable platform 5. To this end and as best shown in Fig. 2, the platform 5 is provided with a plurality of holding means generally designated by the numeral 7. These holding means 7 may constitute an abrupt abutment 8 together with an inclined surface 9; the abutment 8 and inclined surface 9 being shown enlarged in Fig. 3. It will be understood that for some applications of the invention it may be possible or desirable to eliminate the inclined surface 9 or the abutment 8. Also it is within the contemplation of the present invention that the surface 9 and abutment 8 could take the form of a simple recess for receiving each can roller. As is indicated by the arrow in Fig. 2 the direction of the rotation of the platform 5 is clockwise. Thus the abutments 8 are disposed on the side of the holding means 7 which is opposite from the direction of rotation of the rotatable platform 5. In this manner the rollers of the can engage the abutment 8 and are securely held thereagainst as the can rotates against the frictional drag effect of the sliver being coiled. Inclined surfaces 9 are disposed on the part of holding means 7 which is in the direction of rotation of the platform. Of course the purpose of the inclined surfaces 9 is to allow the can to be gradually lowered from the main portions 10 of the platform face into the holding means and into engagement with abutments 8 and to impede rotation of can 4 in a clockwise direction relative to platform 5.

For the purpose of guiding the rollers into proper engagement with the abutments 8 forming a part of the holding means 7, i.e. in order to properly center the can 4 on the rotatable platform 5, guide means in the form of the outer guide elements 11 are provided. In addition, 35 the inner guides 12 are also provided in spaced relation to the outer guide elements 11. Thus with the can positioned in approximately its correct position on the platform 5 rotary motion is imparted to can 4 manually in a counter clockwise direction and causes each of the 40 rollers to ride between one of the outer guides 11 and its associated inner guide 12 and thereby causes each roller to assume its position within one of the holding means 7.

In Fig. 2 the platform 5 is made up of an outer annular part 5A and an inner circular part 5B secured to the outer 45 part by bolts 5C. Also in Fig. 2 the inner guides 12 extend only to the inner edge of annular part 5A.

As is shown in Fig. 4 the platform 5 may be constructed of one piece secured in place by bolts 5D and the inner guides 12A may extend into the center 5F of the platform 5 where they unite. By the construction of Fig. 4 the 50 rollers are positively guided irrespective of the particular relation between can 4 and platform 5 so long as one or more rollers is in engagement with the platform. The arrangement of Fig. 4 is the presently preferred arrangement.

Preferably the rollers used in our invention are of the swivel type because such rollers are not subject to congestion by lint. As is best shown in Fig. 3, each of these rollers comprises a rotatable wheel 13 which is mounted 60 on an axle 14 secured to a yoke member 15 comprising a pair of spaced legs 15A and 15B and a bight portion 15C through which a swivel pin 16 extends. Pin 16 is anchored in a plate 17 affixed by bolts 18 and nuts 19 to a spider 20. Spider 20 preferably is in the form of a 65 triangle of unitary construction and is secured to the can by set screws 21 which engage the flange of can 4 to hold the swivelled rollers in place.

Can 4 is provided with a bottom 22 whose edge 22A is gripped between the flange ring 23 and the can wall 24. A reinforcing skirt 25 is mounted about the lower edge of can wall 24 and the flange assembly is held together by a plurality of units 26. The manner of

mounting the swivel rollers 6 to the can is claimed in copending application Serial Number 747,232, filed July 8, 1958 and assigned to the assignee of this invention.

While we have shown and described certain forms of the invention we do not wish to be limited thereto and intend in the appended claims to cover all changes and modifications which fall within the true spirit and scope of the invention.

What we claim is:

1. A sliver coiler comprising a rotatable platform, a sliver can adapted for removable mounting on said platform, a plurality of rollers affixed to the bottom of said can, a plurality of roller holding means on said platform corresponding to said plurality of rollers on said can, each roller holding means being engageable with one of said rollers to prevent substantial relative movement between said can and said platform, and a plurality of roller guide means on said platform corresponding to said plurality of roller holding means, each roller guide means being engageable with one of said plurality of rollers and being effective to guide such roller into cooperative relation with the associated roller holding means in coordination with relative movement between said can and said platform while said can is mounted on said platform.

2. A sliver coiler comprising a rotatable platform, a sliver can adapted for removable mounting on said platform, a plurality of rollers affixed to the bottom of said can, a plurality of roller holding means on said platform corresponding to said plurality of rollers on said can, each roller holding means being engageable with one of said rollers to prevent substantial relative movement between said can and said platform, and a plurality of roller guide means on said platform corresponding to said plurality of roller holding means, each roller guide means being disposed to impart a component of movement to one of said rollers upon engagement therewith which is in a radial direction relative to said platform in response to predetermined angular movement of said can relative to said platform while said can is mounted thereon.

3. A sliver coiler comprising a rotatable platform, a sliver can adapted for removable mounting on said platform, a plurality of rollers affixed to the bottom of said can, a plurality of roller holding means on said platform corresponding to said plurality of rollers on said can, each roller holding means being engageable with one of said rollers to prevent substantial relative movement between said can and said platform, and a plurality of roller guide means on said platform corresponding to said plurality of roller holding means, each roller guide means comprising a guide element extending to its associated roller holding means from a point more remote from the center of rotation of said platform than such roller holding means and spaced therefrom in the direction of rotation of said platform, each guide element being engageable with one of said plurality of rollers and being effective to guide such roller into cooperative relation with the associated roller holding means in coordination with relative movement between said can and said platform while said can is mounted on said platform.

4. A sliver coiler comprising a rotatable platform, a sliver can adapted for removable mounting on said platform, a plurality of rollers affixed to the bottom of said can, a plurality of roller holding means on said platform corresponding to said plurality of rollers on said can, each roller holding means being engageable with one of said rollers to prevent substantial relative movement between said can and said platform, and a plurality of roller guide means on said platform corresponding to said plurality of roller holding means, each roller guide means comprising a guide element extending to its associated roller holding means and a part of which is angularly spaced therefrom and disposed generally be-

tween such roller holding means and the center of said platform, each guide being engageable with one of said plurality of rollers and being effective to guide such roller into cooperative relation with the associated roller holding means in coordination with relative movement between said can and said platform while said can is mounted on said platform.

5. A sliver coiler comprising a rotatable platform, a sliver can adapted for removable mounting on said platform, a plurality of rollers affixed to the bottom of said can, a plurality of roller holding means on said platform corresponding to said plurality of rollers on said can, each roller holding means being engageable with one of said rollers to prevent substantial relative movement between said can and said platform, and a plurality of roller guide means on said platform corresponding to said plurality of roller holding means, each roller guide means comprising a pair of spaced guide elements extending to their associated roller holding means and defining a raceway for receiving one of said rollers and for guiding such roller into cooperative relation with the associated roller holding means in response to predetermined relative movement between said can and said platform while said can is mounted on said platform.

6. A sliver coiler comprising a rotatable platform, a sliver can adapted for removable mounting on said platform, a plurality of rollers affixed to the bottom of said can, a plurality of roller holding means on said platform corresponding to said plurality of rollers on said can, each roller holding means comprising an abutment on said platform engageable with one of said rollers to prevent substantial relative movement between said can and said platform, and a plurality of roller guide means on said platform corresponding to said plurality of roller holding means, each roller guide means being engageable with one of said plurality of rollers and being effective to guide such roller into cooperative relation with the associated roller holding means in coordination with relative movement between said can and said platform while said can is mounted on said platform.

7. A sliver coiler comprising a rotatable platform, a sliver can adapted for removable mounting on said platform, a plurality of rollers affixed to the bottom of said can, a plurality of roller holding means on said platform corresponding to said plurality of rollers on said can, each roller holding means comprising an abrupt abutment on the part of such holding means which is disposed in a direction opposite to the direction of rotation of said platform and a gradual incline on the part thereof which is disposed in the direction of rotation of said platform, each holding mean being engageable with one of said rollers to prevent substantial relative movement between said can and said platform, and a plurality of roller guide means on said platform corresponding to said plurality of roller holding means, each roller guide means being engageable with one of said plurality of rollers and being effective to guide such roller into cooperative relation with the associated roller holding means in coordination with relative movement between said can and said platform while said can is mounted on said platform.

8. A sliver coiler comprising a rotatable platform, a sliver can adapted for removable mounting on said platform, a plurality of swivel type rollers affixed to the bottom of said can, a plurality of roller holding means on said platform corresponding to said plurality of rollers on said can, each roller holding means being engageable with one of said rollers to prevent substantial relative movement between said can and said platform, and a plurality of roller guide means on said platform corresponding to said plurality of roller holding means, each roller guide means comprising a guide element extending to its associated roller holding means from a point on said platform which is angularly displaced from such roller holding means, said guide element being dis-

posed to impart a component of movement to one of said rollers which is in a radial direction relative to said platform in response to predetermined angular movement of said can relative to said platform while said can is mounted thereon.

9. A sliver coiler comprising a rotatable platform, a sliver can adapted for removable mounting on said platform, a plurality of rollers affixed to the bottom of said can, a plurality of roller holding means on said platform corresponding to said plurality of rollers on said can, each roller holding means comprising an abrupt abutment forming the part thereof which is opposite to the direction of rotation of said platform and a gradual incline forming the part thereof which is in the direction of rotation of said platform, each holding means being engageable with the corresponding roller to prevent substantial relative movement between said can and said platform, and a plurality of roller guide means on said platform corresponding to said plurality of roller holding means, each roller guide means comprising a pair of spaced guide elements extending to their associated roller holding means and defining a raceway for receiving one of said rollers and for guiding such roller into cooperative relation with the associated roller holding means in response to predetermined relative movement between said can and said platform while said can is mounted on said platform.

10. A sliver coiler comprising a rotatable platform, a sliver can adapted for removable mounting on said platform, a plurality of rollers affixed to the bottom of said can, a plurality of roller holding means on said platform corresponding to said plurality of rollers on said can, each roller holding means being engageable with one of said rollers to prevent substantial relative movement between said can and said platform, and a plurality of roller guide means on said platform corresponding to said plurality of roller holding means, each roller guide means comprising an acute guide element one end of which is disposed adjacent its associated roller holding means and the other end of which is less remote from the center of rotation of said platform than said one end and which is angularly spaced therefrom in the direction of rotation of said platform, each guide element being engageable with one of said plurality of rollers and being effective to guide such roller into cooperative relation with the associated roller holding means in coordination with relative movement between said can and said platform while said can is mounted on said platform.

11. A sliver coiler comprising a rotatable platform, a sliver can adapted for removable mounting on said platform, a plurality of rollers affixed to the bottom of said can, a plurality of roller holding means on said platform corresponding to said plurality of rollers on said can, each roller holding means being engageable with one of said rollers to prevent substantial relative movement between said can and said platform, and a plurality of roller guide means on said platform corresponding to said plurality of roller holding means, each roller guide means comprising a generally arcuate guide element one end of which is disposed adjacent its associated roller holding means and the other end of which coincides substantially with the center of rotation of said platform, each guide element being engageable with one of said plurality of rollers and being effective to guide such roller into cooperative relation with the associated roller holding means in coordination with relative movement between said can and said platform while said can is mounted on said platform.

12. A circular rotatable platform for sliver coilers comprising a plurality of abrupt abutments angularly disposed about said platform and spaced radially a substantially uniform distance from the center thereof, and a plurality of gradually inclined surfaces adjacent each abutment and disposed therefrom in the direction of rotation of said platform.

13. A circular rotatable platform for sliver coilers comprising a plurality of abrupt abutments angularly disposed about said platform and spaced radially a substantially uniform distance from the center thereof, a plurality of gradually inclined surfaces adjacent each abutment and disposed therefrom in the direction of rotation of said platform, and a pair of radially spaced guides disposed on opposite sides of each of said inclined surfaces.
